UNITED STATES PATENT OFFICE.

JOHN H. McCONNELL, OF AMSBRY, PENNSYLVANIA, ASSIGNOR OF ONE-FOURTH TO
JOHN A. MURRAY, ONE-FOURTH TO V. A. MURRAY, AND ONE-FOURTH TO E. M.
McCONNELL, ALL OF PATTON, PENNSYLVANIA.

TOY PISTOL.

1,115,954.

Specification of Letters Patent.

Patented Nov. 3, 1914.

Application filed September 5, 1912, Serial No. 718,719. Renewed May 28, 1914. Serial No. 841,650.

To all whom it may concern:

Be it known that I, JOHN H. McCONNELL, a citizen of the United States, residing at Amsbry, in the county of Cambria, State of Pennsylvania, have invented certain new and useful Improvements in Toy Pistols; and I do hereby declare the following to be a full, clear, and exact description of the invention, such as will enable others skilled in the art to which it appertains to make and use the same.

The present invention is directed to new and useful improvements in toy pistols, and has for its object to so construct an article of this character that a marble or the like may be projected from the barrel with great force and accuracy.

A further object of the invention is to provide a new and novel means of retaining the marble within the barrel previous to the expelling of the same, thereby permitting the toy to be held in any position without accidental displacement of the marble.

With these and other objects in view, this invention resides in the novel features of construction, formations, combinations and arrangements of parts to be hereinafter more fully described, claimed and illustrated in the accompanying drawing, in which:

Figure 1 is a side elevation of the device. Fig. 2 is a longitudinal sectional view through the same. Fig. 3 is a sectional view on line 3—3 of Fig. 1. Fig. 4 is a similar view on line 4—4 of Fig. 1.

Referring to the drawing, the numeral 1 represents the stock, the same being formed from wood and is provided with a shoulder 2, a transverse groove 3 being formed between the base of the shoulder and stock. Extending from the stock is a reduced extension 4 which has formed centrally thereof a bore 5, said bore terminating in a bore 6 formed in the stock.

Slidably mounted in the bores 5 and 6 is a rod 7, one end of which passes through the perforation 8 formed in the semi-circular plate 9, said plate being secured to the shoulder 2 and has its lower edge resting in the groove 3. The plate 9 serves as

a stop or wear plate for the operating knob 10 carried by the extended end of the rod 7. To the other end of the rod 7 is secured a disk 11, the coil spring 12 having one end resting thereagainst and the other end 55 against the extension 4.

A barrel 13 is provided and is adapted to have its inner end encircle the extension 4. Formed in the sides of the barrel, and adjacent the outer end thereof are diametrically opposite slots 14 and in which operate the hooked ends 15 of the spring arms 16, the inner ends of said arms resting upon the flattened surfaces 17 formed upon the sides of the extension 4. When the barrel 13 is in place 65 screws are passed through the perforations 17' formed therein and through the perforations 18 formed in the inner ends of the arms 16, said screws not only serving to hold the barrel, but also the spring arms in 70 place.

Formed in the under surface of the stock 1 is a recess 19 in which is pivotally mounted the trigger 20, said trigger having an extension 21 adapted to engage in the annular 75 groove 22 formed in the rod 7 and to hold the same in the position so as to compress the spring 12.

In use a marble or the like is forced in the barrel which causes the spring arms 16 80 to flex outwardly during the passage of the marble in the barrel, it being of course understood that the rod has been operated to be engaged by the trigger, said springs after the marble has been inserted the proper distance will grip the same and prevent accidental displacement of the same. Upon the trigger being operated the rod will be forced outwardly by the spring 12, and as the marble rests against the disk 11 the same will 85 be projected from the barrel.

What is claimed is:—

A toy pistol comprising a stock having an extension formed thereon, a bore passing through the extension and stock a recess 95 formed in the stock, a trigger pivotally mounted in the recess and having one end projected into the bore, spring arms having their inner ends secured to the extension, a spring pressed rod slidably mounted in the 100

bore, a barrel having its inner end provided with perforations, said barrel being adapted to encircle the extension for a certain distance of its length, perforations formed in the inner ends of the spring arms, and securing devices passable through the perforations of the barrel and the arms to engage the stock, slots formed in the barrel

and in which operate the outer hooked ends of said spring arms.

10

In testimony whereof, I affix my signature, in presence of two witnesses.

JOHN H. McCONNELL.
